(57) **CLAIM**

We claim the ornamental design for a handle for food service equipment, as shown and described.

DESCRIPTION

FIG. 1 is a front perspective view from above of the claimed design;

FIG. 2 is a front view of the claimed design;

FIG. 3 is a rear view of the claimed design;

FIG. 4 is a right side view of the claimed design;

FIG. 5 is a left side view of the claimed design;

FIG. 6 is a top view of the claimed design; and,

FIG. 7 is a bottom side view of the claimed design.

The broken lines in the drawings are included for the purpose of illustrating the unclaimed portions of the article and form no part of the claimed design.

1 Claim, 6 Drawing Sheets
